DESIGN FOR A RECEPTACLE FOR PERFUME
BOTTLES OR THE LIKE

Theodore J. Ignall, Sunnyside, Long Island, and Ernest Penker, Astoria, N. Y., assignors to Cardinal Parfums, Inc., New York, N. Y., a corporation of New York

Application April 20, 1939, Serial No. 84,418

Term of patent 3½ years

To all whom it may concern:

Be it known that we, Theodore J. Ignall, a citizen of the United States and a resident of Sunnyside, Long Island, New York, and Ernest Penker, a citizen of the United States and a resident of Astoria, Long Island, New York, have invented a new, original, and ornamental Design for a Receptacle for Perfume Bottles or the like, of which the following is a specification, reference being had to the accompanying drawing, forming part thereof in which:

Figure 1 is a perspective view looking towards the front of a receptacle for perfume bottles or the like, showing our new design.

We claim:

The ornamental design for a receptacle for perfume bottles or the like, as shown and described.

THEODORE J. IGNALL.
ERNEST PENKER.
